UNITED STATES PATENT OFFICE.

HUMPHREY O'SULLIVAN, OF LOWELL, MASSACHUSETTS.

DESIGN FOR A SOLE.

SPECIFICATION forming part of Design No. 31,381, dated August 8, 1899.

Application filed July 12, 1899. Serial No. 723,616. Term of patent 14 years.

To all whom it may concern:

Be it known that I, HUMPHREY O'SULLIVAN, a citizen of the United States, residing at Lowell, in the county of Middlesex and State of Massachusetts, have invented and produced a certain new and original Design for a Sole; and I do hereby declare the following to be a full, clear, and exact description of the invention, such as will enable others skilled in the art to which it appertains to make and use the same.

The accompanying drawing is a perspective view of the sole.

As shown in the drawing, the leading and material feature of my design consists of a sole-shaped body thicker in its fore part than

in its shank part and provided with five substantially hemispherical-shaped projections on the fore part thereof, located one near the toe and two on each margin, substantially as shown in the drawing.

Having thus described my invention, I claim as new and desire to secure by Letters Patent—

The design for a sole substantially as shown and described.

In testimony whereof I affix my signature in presence of two witnesses.

HUMPHREY O'SULLIVAN.

Witnesses:

HORACE VAN EVEREN,
T. HART ANDERSON.
